AIRPLANE TOY

Frank L. Murphy, Dorchester, Mass.

Application November 8, 1946, Serial No. 708,629

3 Claims. (Cl. 272—31)

1

This invention relates to an airplane toy and more particularly to a structure for causing the propulsion of the airplane about a circular path so that it can be aimed at by a toy anti-aircraft gun.

It is an object of the present invention to provide a structure for causing an airplane to take a circular path automatically when a spring device has been released to set the structure in motion and wherein the airplane not only may be driven through a circular path but also may be caused to dip while in its movement to resemble a dive bomber.

It is another object of the present invention to provide a simple arrangement for causing an airplane to move in a circular path and to dip while moving in this path, which can be easily constructed and which is efficient in operation.

For other objects and for a better understanding of the invention reference may be had to the following detailed description taken in connection with the accompanying drawing, in which:

Figure 1 is an elevational view partly in section showing the operating structure to which an airplane is connected and by which the airplane is given a circular and dipping movement when the structure is released and showing an anti-aircraft gun on a common base with the operating structure whereby shots may be taken at the airplane as it passes over the gun.

Figure 2 is a top plan view of the operating structure and of the airplane.

Referring now to the figures, 10 represents an operating structure, 11 is the airplane adapted to be operated by the operating structure and caused to be given a circular and dipping movement, and 12 is an anti-aircraft gun by which shots can be made at the airplane 11 as it passes by. The operating structure 10 comprises a sleeve 13 having a laterally extending bracket arm 14 near its upper end. This sleeve 13 has a coil spring 15 anchored to its lower end. Extending upwardly through the sleeve is a stationary member 16 fixed to a bottom face 17 on which the operating structure 10 is supported and also upon which is supported the toy gun 12. The spring 15 is held within a housing 18 and its outer end is anchored by an angle member 19 secured to the bottom of the housing by a screw 21. If the spring is to be wound the sleeve 13 is rotated or turned upon the vertically extending fixed support 16. Thereafter the sleeve can be released and the airplane will be moved in a circular and downward dipping path automatically as the spring 15 is unwound from its wound up position.

2

On the outer end of the bracket arm 14 there is pivoted as indicated at 22 a balance arm 23 to the outer end of which, as indicated at 24, the airplane 11 is connected. The bracket arm 14 is supported by a brace 25 extending between the arm and the side of the sleeve 13. The upper end of the pivot arm 23 is connected, as indicated at 27, to a flexible cord 28 which is secured at its outer end, as indicated at 29, to a laterally extending portion 31 on the upper end of the vertically extending fixed member 16 lying within the sleeve 13.

The cord 28 is of less length than the laterally extending portion 31. As the sleeve 13 is released the arm 14 is carried around and with it the pivot arm 23 containing the airplane 11 will be swung about the fixed support 16 and about the laterally extending portion 31 thereof. When the arm 14 becomes at a station below the laterally extending portion 31, the tension upon the cord 28 lessens and the pivot arm 23 to which the airplane or bomber 11 is attached will dip and the airplane will swing at its lowest point. When the pivot arm 23 is diagonally opposite to the laterally extending portion 31 the cord 28 is drawn tight causing the upper end of the pivot arm to be pulled down and thus causing the bomber to be rotated at its highest point of travel. It will thus be apparent that not only does the bomber travel in a circular path but there is a dipping motion to resemble that of a dive bomber. The bomber will dip down and then will come upwardly to its high point. All the while the child can be taking shots with the toy anti-aircraft gun to see if he may hit the airplane 11. The toy gun 12 can be located at any position upon the base 17.

Having thus described the invention, what is claimed is:

40. 1. A toy airplane operating device for giving to the airplane a circular motion or travel in a circular path comprising a vertically extending sleeve having a laterally extending arm thereon, a pivot arm attached to the outer end of the laterally extending arm for movement therewith, an airplane connected to the outer end of the pivot arm, a central member extending upwardly through the sleeve, a base for retaining the central member in its vertically extended position, and means for connecting the upper end of the central vertically extending member to the inner end of the pivot arm, and means for causing the rotation of the sleeve about the fixed vertical central member, whereby the airplane will be extended through a circular path.

2. A toy airplane-operating device for giving to the airplane a circular motion or travel in a circular path comprising a vertically-extending sleeve having a laterally-extending arm thereon, a pivot arm attached to the outer end of the laterally-extending arm for movement therewith, an airplane connected to the outer end of the pivot arm, a central member provided with a laterally-extended portion on its upper end extending upwardly through the sleeve, said pivot arm extending to a point over the laterally-extending portion of said central member, means embodying a flexible cord for connecting the inner end of the pivot arm and the outer end of the laterally-extended portion of said central member, and means for causing the rotation of the sleeve about the central member, whereby the airplane will be extended through a circular path, said cord being of a less length than the laterally-extending portion of the central member, whereby as the airplane is rotated not only will it be given a circular path, but a dipping movement of the airplane resembling that of a dive will be effected, the laterally-extending arm of the sleeve when passing under the laterally-extending portion of the central member permitting the cord to be loosened and thereby allow the outer end of the pivot arm to dip downwardly as it passes under the laterally-extending portion.

3. A toy airplane-operating device for giving to the airplane a circular motion or travel in a circular path comprising a vertically-extending sleeve having a laterally-extending arm thereon,

5 a pivot arm attached to the outer arm of the laterally-extending arm for movement therewith, an airplane connected to the outer end of the pivot arm, a central member provided with a laterally-extended portion on its upper end extending upwardly through the sleeve, said pivot arm extending to a point over the laterally-extending portion of said central member, means embodying a flexible cord for connecting the inner end of the pivot arm and the outer end of the laterally-extended portion of said central member, and means for causing the rotation of the sleeve about the fixed vertical central member, whereby the airplane will be extended through a circular path, said cord being of a less length than the laterally-extending portion of the central member, whereby as the airplane is rotated it not only will be given a circular path but a dipping movement of the airplane resembling that of a dive bomber will be effected, the laterally-extending arm of the sleeve when passing under the laterally-extending portion of the central member permitting the cord to be loosened and thereby allowing the outer end of the pivot arm to dip downwardly as it passes under the laterally-extending portion, said means for effecting the operation of the sleeve comprising a spring adapted to be wound and which spring is connected to the sleeve to cause its operation when the spring is released.
